UNITED STATES PATENT OFFICE.

EPAMINONDAS CLARK, OF NEW YORK, N. Y.

NASAL LIQUID-INHALER.

1,130,961.

Specification of Letters Patent.

Patented Mar. 9, 1915.

Application filed September 16, 1914. Serial No. 861,928.

To all whom it may concern:

Be it known that I, EPAMINONDAS CLARK, a citizen of the United States of America, residing in the borough of Queens, city of New York, in the county of Queens and State of New York, have invented a certain new and useful Improvement in Nasal Liquid-Inhalers, of which the following is a specification, reference being had therein to the accompanying drawings, forming part thereof.

My invention relates to apparatus or devices for use in the treatment of the nasal membranes and throat for the prevention or cure of catarrh, hay fever, and similar troubles.

Heretofore various atomizing or spraying devices have been employed; also "douches" and "irrigators," for forcing liquid into the nasal passages through the nostrils. It is impossible to effectively reach all the nasal cavities with a spray and it is also impossible to effectively force liquid into and fill the nasal cavities against the resisting pressure of air contained therein.

An important object of my invention is to fill the nasal cavities with medicinal liquid, and, in this connection, a more particular object is to remove the air from the nasal cavities by the inhaling power of the lungs, with the head bent forward, so that atmospheric pressure will fill the nasal cavities with the cleansing or curative liquid and free escape of air backward to the lungs is permitted, and also so that the liquid can be retained in the nasal cavities.

Another object of my invention is a highly sanitary construction having few parts of such material and construction that they will not readily collect unsanitary accumulations and which can be quickly and thoroughly sterilized.

Other objects of my invention are durability, simplicity of construction, inexpensiveness of manufacture, convenience and comfort in use, portability, and other objects and advantages which will hereinafter appear.

My invention includes features of construction and combination of parts, as will appear from the following description.

I shall now describe the nasal liquid inhaler embodying my invention illustrated in the accompanying drawings and shall thereafter point out my invention in claims.

Figure 1 is a reduced elevation of the

nasal liquid inhaler with the cover cap removed and as held for use. Fig. 2 is an elevation of the complete device. Fig. 3 is a central vertical section of the same.

The nasal liquid inhaler embodying my invention illustrated in the accompanying drawings comprises, in combination, three separable parts, all of which are preferably made of glass, and that is the material indicated in the drawings. A liquid-container or liquid-containing receptacle 1 is shown as of general bottle form, having a slightly inwardly curved bottom *a* providing a flat annular peripheral base, polygonal slightly upwardly tapered side walls *b*, and a short tapered cylindrical neck *c* providing a comparatively wide mouth at the top of the container 1, the neck *c* being joined to the side walls *b* by a small offset or shoulder *d*, the neck *c* being shown as having an outer annular groove at its base.

A straight imperforate air-excluding liquid-conveying and liquid-inhaling suction tube 2, open at both ends, is supported in a substantially upright position in the container 1 and projects at its upper end from the mouth of the container. At its upper end, the inhaling tube 2 is provided with a rounded upwardly tapered bulb *e*, forming an inner liquid-holding enlargement and being of cone-shape for slightly entering the nostril (Fig. 1), the bulb *e* being of sufficient size to form air-excluding fluid-tight communication at the nostril with the nasal passages. Below the terminal tapered bulb *e*, a narrow annular constriction or throat *f* separates the bulb *e* from a cylindrical liquid-holding enlargement or reservoir *g* shown as of about the same diameter as the largest diameter of the bulb *e*, the length of the reservoir *g* being shown as nearly the same as that of the bulb *e*. The reservoir *g* gradually merges by rounded curves into a downwardly tapered lower stem *h*, the stem *h* being shown as of a little more than one-half the total length of the inhaling tube 2. The inhaling tube 2 is shown as having walls of substantially uniform thickness throughout.

At the lower end of the stem *h* the wall of the stem is longer at one place on the stem than it is at another place, so as to provide for the free entrance of the liquid at the bottom of the stem at the sides of the longer portion of the wall with the tube 2 resting on its lower end and supported on

the bottom *a* of the liquid-container 1, as appears in the drawings. In the inhaling tube 2 illustrated in the drawings, the lower end of the stem *h* is shown as beveled 5 so as to provide a notch for the free entrance of the liquid from the container 1 to the lower end of the stem *h* of the inhaling tube 2. The liquid-admitting opening provided through this notch at the lower end 10 of the stem *h* should be of as great area as the lower end of the stem *h*, so that the liquid can flow freely into the stem *h* of the inhaling tube.

The liquid-holding enlargement or reservoir *g* is shown as located mostly in the neck *c* of the container 1, and the upper liquid-holding terminal bulb *e* is shown as projecting upward above the top of the neck *c*, the throat *f* being just above the top 20 of the container 1. The inhaling tube 2 fits loosely in the neck *c* forming the mouth of the liquid-container 1, as clearly appears in Fig. 3, so that this tube may be freely lifted out of or inserted in the container 1 and also 25 so as to provide free entrance of atmospheric air to the container 1 at the mouth of the container around the inhaling tube 2. The upwardly tapered bulb *e* projects sufficiently from the mouth of the liquid-container 1 30 for convenient use, as indicated in Fig. 1, without any interference of the container.

A slightly upwardly tapered cup-shaped cover cap 3 fits closely over the top of the container 1, forming a closure therefor and inclosing and completely covering the inhaling tube 2, a tapered ground joint being provided between the outer tapered surface of the neck *c* and the inner flaring co-operative surface of the cover cap 3. Besides 40 forming a tight closure for the container 1, inclosing the inhaling tube 2, the cover cap may be conveniently used as a small cup for gargling the throat.

In the operation of the device, the liquid-container 1 is filled conveniently full of preventative or curative liquid and the inhaling tube 2, previously removed, is placed therein. The container 1 is made of the correct 45 size or capacity to contain the proper quantity of the liquid for one inhalation, an extra supply of the liquid being kept in a separate suitable, larger receptacle or bottle. For convenient use the container should be held in the hand with the tapered bulb *e* 50 tightly in the nostril at the same side, and the other nostril closed by pressure of the thumb of the other hand, the forefinger of the same hand conveniently being placed at the other side of the nose at the bridge of the nose (Fig. 1), in position ready for use 55 to press upon and close that nostril to retain the liquid after the inhalation is completed. The end of the forefinger or the thumb, as illustrated in Fig. 1, of the hand holding the container 1 should be pressed

into the depression formed at the outside of the inhaling tube 2 by the throat *f*, to hold the tube firmly and also to draw the inhaling tube 2 away from the nostril after the inhalation, as otherwise it might have a tendency to stick, particularly by reason of the pressure of the finger in closing the nostril. 70

The head should be inclined well forward, such as with the chin upon the chest (Fig. 1), and all of the medicinal liquid, an ounce or more, drawn up by a single deep inhalation. The forward position of the head will enable the air, without liquid, to pass back into the lungs and the liquid will run downward and forward and fill the nasal cavities, 80 where it may be readily retained for any desired length of time, for example, from one to two minutes, in actual intimate contact with the lining membranes of the nasal passages and cavities. It should be noted that the 85 head must be inclined forward in order to use the device of my invention, and that the devices commonly heretofore employed cannot be used with the head bent forward. The device of my invention can also be 90 equally well used for drawing the liquid back through the air passage into the throat when it is desired to do so.

The construction of the inhaling tube 2 is such that substantially all of the liquid 95 can be drawn not only from the container 1, but also the liquid in the tube itself can be drawn up until the tube is empty. The stem *h*, having the liquid entrance at its lower end, the reservoir enlargement *g*, the restricted throat *f* and the tapered liquid holding bulb *e* all contribute to this result of enabling the use of all the liquid from the container 1 and inhaling tube 2, 100 and also contribute to rendering the elevation of the liquid easy. The enlargement *g* and bulb *e*, particularly the former, both act as secondary reservoirs or liquid holders for the liquid. In starting the inhalation, the container 1 being full, so that the level or 110 upper surface of the liquid is high, the liquid is correspondingly easily drawn up through the inhaling tube 2 into the nose; and the liquid-holding enlargement or reservoir *g* and nostril-closing bulb *e* are filled 115 out of the first easily drawn up liquid. As the inhalation continues, the container 1 is first emptied, the inhaling tube 2, including the bulb *e* and reservoir *g*, being still filled with the liquid. The inhalation continuing, 120 atmospheric air raises the liquid up the comparatively small stem *h* and then successively impels the liquid up from the liquid-holding enlargement or reservoir *g* and bulb *e*. The short distances which these 125 reservoir supplies or secondary supplies of the liquid are lifted from the reservoir *g* and bulb *e*, make the last of the inhalation effort much easier than if the last remnant of the liquid had to be elevated from the bottom *a* 130

of the container 1 at the lower end of the stem 9. The constriction or throat *f* assists in preventing the last of the liquid from breaking up into separated drops or spray 5 and the consequent entrance of air into the nose with the liquid, the effect of which would be to strangle the user.

It should be noted that the entire construction is such that the complete device 10 may be kept in sanitary condition. The device admits of easy packing for shipment or for the user to carry with him, and when not in use the device is merely set aside, all the interior parts, including all surfaces of 15 the inhaling tube 2, being protected from dust. All surfaces of the three glass parts of the device may be readily washed and sterilized. It is obvious that various modifications may be made in the construction 20 shown in the drawings and above particularly described within the principle and scope of my invention.

I claim:

1. A nasal liquid inhaler comprising a 25 substantially straight liquid-inhaling suction tube open at both ends and having at its upper end a liquid-holding bulb having a constriction forming a throat below the bulb and having an enlargement forming a liquid-holding reservoir below the throat.
2. A nasal liquid inhaler comprising a liquid-container having a mouth at the top, and a substantially straight liquid-inhaling suction tube open at both ends loosely supported in the container and projecting at its upper end from the mouth of the container, the inhaling tube having at its upper end a bulb tapered toward the open upper end of the inhaling tube to form fluid-tight communication with the nasal passages at the nostril, the inhaling tube also having a reduced lower stem and a liquid-holding enlargement forming a reservoir above the stem, and having a constriction separating 45 the reservoir and the bulb, a free entrance for the liquid being provided to the stem at the lower end of the inhaling tube and the inhaling tube fitting loosely in the mouth of the container to provide free entrance of air to the container.
3. A nasal liquid inhaler comprising a substantially straight liquid-inhaling suction tube open at both ends and having at its upper end a bulb tapered toward the open 55 upper end of the inhaling tube to form fluid-tight communication with the nasal passages at the nostril, the inhaling tube having a liquid-holding enlargement forming a reservoir below the bulb and a constriction separating the bulb and the reservoir, the inhaling tube having a reduced stem below the reservoir.
4. A nasal liquid inhaler comprising a liquid-container having a mouth at the top, and a substantially straight liquid-inhaling 65

suction tube open at both ends loosely supported on the bottom of the container and projecting at its upper end from the mouth of the container, the inhaling tube having a lower stem, the wall of the stem being longer 70 at one place than at another place to provide an opening for the free entrance of the liquid to the inhaling tube with the inhaling tube resting on the end of the stem and having at its upper end a bulb tapered toward the open upper end of the inhaling tube to form fluid-tight communication with the nasal passages at the nostril, the inhaling tube fitting loosely in the mouth of the container to provide free entrance of air to the 80 container.

5. A nasal liquid inhaler comprising a liquid-container having a mouth at the top, a substantially straight liquid-inhaling suction tube open at both ends loosely supported on the bottom of the container and projecting at its upper end from the mouth of the container, the inhaling tube having a lower stem, the wall of the stem being longer at one place than at another place to provide an opening for the free entrance of the liquid to the inhaling tube with the inhaling tube resting on the end of the stem, and having at its upper end a bulb tapered toward the open upper end of the inhaling tube to form fluid-tight communication with the nasal passages at the nostril, the inhaling tube fitting loosely in the mouth of the container to provide free entrance of air to the 90 container, and a cup-shaped cover cap 95 fitting closely over the top of the container to form a closure therefor inclosing the inhaling tube.

6. A nasal liquid inhaler comprising a liquid-container having a mouth at the top, and a substantially straight liquid-inhaling suction tube open at both ends loosely supported on the bottom of the container and projecting at its upper end from the mouth of the container with sufficient looseness to provide free entrance of air to the container, the inhaling tube having throughout substantially the lower half of its length a gradually downwardly tapered stem provided at its lower open end with longer and shorter wall portions for the free entrance of the liquid to the tube beneath the shorter wall portion with the tube resting upon the longer wall portion, the inhaling tube having a liquid-holding enlargement forming a reservoir into which the upwardly flaring stem gradually merges, a constricted throat above the reservoir, and a terminal bulb above the constricted throat, the bulb being tapered toward the open upper end of the tube to form fluid-tight communication with the nasal passages at the nostril.

7. A nasal liquid inhaler comprising a substantially straight liquid-inhaling suction tube open at both ends having at its

- 4
- 130 open upper end an upwardly tapered bulb, having a constriction forming a throat below the bulb, having an enlargement forming a reservoir below the constricted throat, and having a downwardly tapered lower stem into which the reservoir gradually merges, the wall of the stem at the lower end being longer at one place than at another to provide for free entrance of liquid to the lower end of the stem with the inhaling tube supported on such longer portion of the wall of the stem.
- 135 8. A nasal liquid inhaler comprising a liquid-container having a mouth at the top, and a substantially straight liquid-inhaling suction tube open at both ends supported in the container and projecting at its upper end from the mouth of the container, the inhaling tube having at its upper end an upwardly tapered bulb, having a constriction forming a throat below the bulb, having an enlargement forming a reservoir below the constricted throat, and having a reduced stem extending downward from the 140 reservoir to the lower end of the tube, a free entrance for the liquid being provided to the stem and a free entrance for air being provided to the container at the mouth of the container.
- 145 9. A nasal liquid inhaler comprising a liquid-container having a mouth at the top, a substantially straight liquid-inhaling suction tube open at both ends supported in the container and projecting at its upper end from the mouth of the container, the inhaling tube having at its upper end an upwardly tapered bulb, having a constriction forming a throat below the bulb, having an enlargement forming a reservoir below the constricted throat, and having a reduced stem extending downward from the 150 reservoir to the lower end of the tube, a 155 free entrance for the liquid being provided to the stem and a free entrance for air being provided to the container at the mouth of the container.
- 160 10. A nasal liquid inhaler comprising a liquid-container having a neck at the top providing a mouth, a substantially straight liquid-inhaling suction tube open at both ends and supported at its lower end upon the bottom of the container and projecting 165 from the mouth of the container at its upper end with sufficient looseness to provide free entrance of air to the container at its mouth, the inhaling tube having at its upper end an upwardly tapered nostril-closing bulb above the top of the container, the inhaling tube having a constriction forming a throat below the bulb, the inhaling tube having a liquid-holding enlargement forming a reservoir below the restricted throat, 170 and the inhaling tube having a gradually downwardly tapered reduced stem into which the liquid-holding reservoir gradually merges, the stem being substantially one-half the entire length of the inhaling tube, the lower end of the wall of the stem projecting farther downward at one place than at another to provide for free entrance of liquid to the lower end of the stem, and a separable cup-shaped cover cap fitting 175 closely over the neck of the container and forming a closure for the container and inclosing the inhaling tube.

In testimony whereof I have affixed my signature in presence of two witnesses.

EPAMINONDAS CLARK.
